(57) **CLAIM**

The ornamental design for a transition garment, as shown and described.

DESCRIPTION

FIG. 1 is an exploded front elevational view of a transition garment showing my new design, shown with the wings detached;

FIG. 2 is an exploded rear elevational view thereof;

FIG. 3 is a front elevational view thereof, shown with both wings attached;

FIG. 4 is a rear elevational view thereof;

FIG. 5 is a front elevational view thereof, shown with one wing detached; and,

FIG. 6 is a rear elevational view thereof.

The broken lines of even length shown in the drawings depict environment and form no part of the claimed design. The broken lines of uneven length shown in the drawings within the transition garment form the boundary of the claimed design. The broken lines of uneven length showing the head and foot in FIG. 3 depict environment that forms no part of the claimed design.
